UNITED STATES PATENT OFFICE

CHARLES WENDT, OF SPOKANE, WASHINGTON

CRUSHING BOARD

Application filed March 20, 1928. Serial No. 263,190.

My present invention relates to an improved crushing board or appliance used in fashioning patterns for designs in cloth or fabric for various purposes and especially designed for use in fashioning linings for burial caskets. The primary object of the invention is the provision of means whereby a symmetrical pattern or design may be fashioned with accuracy and uniformity in the material with a minimum expenditure of time and labor.

In the formation of the lining a backing of strong and durable material, such as cheesecloth, is employed as the base, to which the facing of silk, cloth, or other suitable material is stitched or basted, and in carrying out my invention the pattern is fashioned in the lining with the facing material beneath and the backing material uppermost. When the design or pattern has been completed on the board the lining is removed while in inverted position and then the completed article is of course turned over with the facing material uppermost and the backing material beneath.

The invention consists in certain novel combinations and arrangements of movable and removable parts combined with a stationary frame whereby the pattern or design is fashioned or formed as will hereinafter be more fully set forth and claimed.

In the accompanying drawings I have illustrated one complete example of the physical embodiment of my invention wherein the parts are combined and arranged according to the best mode I have so far devised for the practical application of the principles of my invention.

While I have illustrated one design or pattern fashioned on the crushing board, it will be understood that other artistic arrangements and combinations of parts may be made whereby the design or pattern can be varied, and it will be apparent that various materials also may be used in the formation of the lining or other completed article.

Figure 1 is a perspective view showing the frame with its movable bars carrying the pattern forming devices, the bars being separated. Figure 2 is a broken perspective view

of the appliances showing a portion of the facing material and the backing material with the movable pattern forming bars in closed position. Figure 3 is a plan view of an artistic pattern fashioned in a lining. 55 Figure 4 is an enlarged view showing one of the figures of the pattern, the figures of course being repeated in the staggered arrangement of rows as seen in Figure 3. Figure 5 is a detail perspective view showing 60 the frame of the appliance. Figure 6 is a detail view showing one end of a removable parting strip. Figure 7 is a transverse vertical sectional view at line 7, 7, of Figure 5. Figure 8 is a transverse vertical sectional 65 view at line 8, 8, of Figure 5. Figure 9 is a detail sectional view showing the movable bars in open position, and Figure 10 is a similar enlarged view showing the bars in closed position. Figure 11 is a perspective 70 view enlarged, showing the bars with the facing material thereon and the transversely arranged parting strips and Figure 12 is a view similar to Figure 11 but with the movable bars in open position. Figure 13 is 75 a perspective view showing a portion of one of the cross bars with a pattern former thereon.

In carrying out my invention I utilize a stationary frame which is of suitable size and shape and provided with side rails 1—1 and rigid cross bars 2, one end of the frame being closed as at 3.

Within the open frame is arranged a central longitudinally extending guide bar 4 85 which is fastened at one end of the frame, and the guide bar is fashioned with side grooves 5 along its upper edges. A stationary or fixed cross bar 6 is fixed to this guide bar with its ends located in grooves 7 fastened at the inner sides of the frame and above the end pieces 3 of the frame. A slide 8 is mounted upon this longitudinal guide bar and the slide has spaced tongues 9 which fit into the grooves 5 of the guide bar to permit 90 longitudinal movement of the slide with relation to the guide bar 4.

At one end of the slide a cross head 10 is fixed with its ends located in the grooves 7, 100 and this cross head of course moves with the

slide when the latter is moved. In addition to the two cross bars 6 and 10, I employ a plurality of intermediate cross bars 11 that are slideable with relation to the slide, and have their ends guided in the grooves 7. The slide cross bars 11 are arranged in parallelism transversely of the longitudinal slide and they rest on this longitudinal slide. The slide cross bars are connected at their lower sides by a plurality of flexible strips 12 fashioned from canvas or other suitable material the ends of the strips being attached to the cross bars 6 and 10. Along the upper edges of these slide cross bars they are bevelled as at 13.

It will be understood that all of the slide bars 11 are relatively movable and before the operation of crushing the material is started these slide bars are spaced apart with the tapes or flexible strips connecting them. The flexible strips, however, permit the slide cross bars to be moved into contact one with another, and this is done after the facing or silk is put in position as will be described. Each of the slide cross bars is provided with a suitable number of spaced pattern formers by means of which the desired figure is fashioned in the facing material of the lining. Each pattern former comprises a post 14 of suitable shape and size which is provided with a rubber cushion 15 against which the silk or other facing material 19 is placed in the formation of the figure of the pattern. The post 14 as seen in Figure 13 is provided with a pair of retaining pins 16 which are pointed to penetrate the silk facing and between these pins is located a headed basting pin 17 at which point the canvas backing 20 is basted to the silk facing 19. The cross bar 11 also has a plurality of pattern forming pins 18 which are headed and it will be apparent that the facing material may also be basted throughout the area of the facing to the backing material at these two pins 18 if necessary for the formation of the pattern in the silk facing.

The lining comprises the facing material 19 of silk or other suitable material, and the backing material 20, which is preferably strong and durable and suitable for the purpose of supporting the facing material. The backing is stitched or basted to the facing at suitable points in order to form the finished product as in Figure 3 before the lining has been removed from the crushing board.

The silk or facing material 19 is first applied to the pattern forming devices while the cross bars are in spaced relation as seen in Figure 1, and removable parting strips or formers 21 are interposed between the staggered rows of the posts of the cross bars, said parting strips being arranged transversely of the cross bars. These parting strips, as best seen in Figure 6, are fashioned with rounded heads 22 and they are of proper size

to rest upon pair of rows of staggered posts. The strips 21 of course depress the silk or facing material to form channels and above these channels the projections or protuberances are fashioned in the facing on the posts. Then the spaced cross bars are pushed together, and the backing material which may be of cheesecloth is stitched or basted to the facing material or silk at the points 17, and in this manner the facing material and the backing material are fastened together to form the lining.

After the pattern has been completed the parting strips 21 are first removed, and then the lining may be lifted from the retaining pins, and of course the inverted lining is turned with the facing side upward and is ready for use.

Having thus fully described my invention what I claim as new and desire to secure by Letters Patent is:—

1. The combination in a crushing board with a frame and a central, longitudinal, guide bar fixed with the frame, a fixed cross bar on the guide bar, a slideable member resting on the guide bar, and a slideable cross bar fixed to said member, intermediate cross bars slideable in the frame and flexible connections between all of said bars, and pattern forming devices on the cross bars.

2. The combination with a frame having opposite lateral grooves, of a cross bar fixed in the grooved frame, a longitudinal centrally disposed guide bar rigid with the cross bar, a slide on the guide bar, a cross bar rigid with the slide and having its ends slideable in the grooves, intermediate cross bars having their ends slideable in the grooves, flexible connections between adjoining bars, and pattern forming devices mounted on all of said intermediate cross bars.

3. The combination with a frame having opposed lateral grooves, of a fixed cross bar, a central, longitudinal bar fixed to the cross bar and provided with parallel edge grooves, a slide having tongues complementary to said edge grooves, a cross bar fixed to the slide and having its ends slideable in the lateral grooves, intermediate cross bars above the slide and longitudinal bar and having their ends slideable in the lateral grooves, flexible connections between adjoining cross bars, and pattern forming devices on said cross bars.

In testimony whereof I affix my signature.

CHARLES WENDT.
